United States Patent

Des. 236,607
Patented Sept. 2, 1975

236,607

OCCUPANT-PROPELLED VEHICLE

Robert L. Bundschuh, West Simsbury, Conn., and Bruce C. Delaplaine, Centerport, N.Y., assignors to Pedicar Corporation

Filed Mar. 6, 1973, Ser. No. 338,642

Term of patent 14 years

Int. Cl. D12—11

U.S. Cl. D12—107

FIG. 1

FIG. 2

FIG. 3

FIG. 4

FIG. 6

FIG. 5

FIG. 1 is a front perspective view of an occupant-propelled vehicle showing our new design;
 FIG. 2 is a left side elevational view thereof;
 FIG. 3 is a right side elevational view thereof;
 FIG. 4 is a top plan view thereof;
 FIG. 5 is a rear elevational view thereof; and
 FIG. 6 is a front elevational view thereof.

We claim:

The ornamental design for an occupant-propelled vehicle, as shown.
